CREEPER FOR BOOTS AND SHOES

Filed April 4, 1927

UNITED STATES PATENT OFFICE.

HIRAM S. COBURN, OF MALDEN, MASSACHUSETTS; LIZZIE J. DEAN EXECUTRIX OF
SAID HIRAM S. COBURN, DECEASED.

CREEPER FOR BOOTS AND SHOES.

Application filed April 4, 1927. Serial No. 180,717.

My invention relates to creepers for attachment to boots or shoes and it has for its object to provide an improved device of this class.

To this end I have provided an improved creeper for boots and shoes having the peculiar features of construction and mode of operation set forth in the following description; the novel features of the invention being particularly pointed out and defined in the claims at the close thereof.

In the accompanying drawings: Figure 1 is a side elevation of my improved creeper illustrating the manner in which it is applied to a boot or shoe.

Figure 2 is a bottom plan view of the creeper shown in Fig. 1.

Figure 3 is a top plan view, partly broken away at its opposite ends, of the creeper shown in Figs. 1 and 2.

Figure 4 is a section on line 4—4 of Fig. 1.

Figure 5 is a section on line 5—5 of Fig. 2.

Figure 6 is a section on line 6—6 of Fig. 1.

As herein shown my improved creeper comprises a sheet metal body member 1 having integral side flaps 2—2 providing ways, upon the top side of the member 1, for adjustable sheet metal end sections 3 and 4. Each end member or section 3 and 4 is made at the

middle of its inner end portion with a spring tongue 5 having a tooth 6 adapted to occupy one of a series of slots 7 provided in the body member 1. These spring tongues fit flatwise against the top side of the body member 1 except that they are provided, intermediate their ends, with an upwardly bowed loop or eye 8 providing for the insertion therein of a pointed tool by means of which the tongue may be lifted to disengage its tooth 6 from the body plate 1 when the end member or section of which it forms part is to be adjusted lengthwise of body member 1.

At its outer end each end member or section 3 and 4 is made with an upstanding abutment ear 9 each formed with a slot 10 to receive the hinge eye 11 of a sheet metal link member 12. That is, the eye 11 is an extension of the sheet metal link 12 and is wrapped around, and pivots on, the cross-bar of the upstanding ear 9 that borders the top of the slot 10.

Each link 12 carries a wire lever 13 fulcrumed at 14, 14 and formed with a centrically disposed loop 15 which constitutes one

of the lever are constituted by the ends to which the reference characters 13 are applied and these ends are adapted to engage the top side of the projecting edge of a sole 8 as shown in Figs. 1 and 4.

At its middle the member 12 is made with a longitudinal slot through which the loop 15 of the lever 13 extends so that one arm of the lever is upon the outside of the member and the other arm thereof, together with its trunnions 14, 14, are disposed upon the opposite side of the member 12. These trunnions 14, 14 which serve as the fulcrum for the lever are rotatably mounted in bearings provided upon brackets 16, 16 made with U-shaped portions embracing the side bars 17 of the member 12. These brackets 16, or rather their U-shaped portions, extend around the inner edges of the side bars 17 and are yieldingly pressed against said inner edges by the spring loop 15. The inner edges of the side bars 17 are serrated or notched to afford sockets to receive cross-bars 18, Figs. 4 and 6, provided at the middle of the U-shaped body portions of the brackets 16 whereby said brackets are normally locked against movement endwise on the side bars 17 of the member 12.

The loop arm 15 of one of the levers 13 has fastened to its middle one end of a spring 19 whose opposite end is fastened to a hook 20 that separably engages the middle portion of the loop arm 15 of the other lever 13.

When the creeper is to be applied to a boot or shoe the brackets 16 are adjusted on the side bars 17 of the member 12 so as to position the same appropriately to the thickness of the sole and so that when the loop arms 15 are swung inwardly into position on top of the shoe, as shown in Fig. 4, the levers 13 engage the top side of the opposite edge portions of the sole and firmly clamp the latter between said levers and the base portion or portions of the creeper. The spring 19 is made of such length that after the loop arms 15 are swung down into position toward the top of the shoe it is necessary to stretch the spring 19 to engage the hook 20 with the opposite loop arm 15 so that when the creeper is in position on the shoe the stress of the spring 19 pulls upon the loop arms 15 thereby maintaining them in gripping engagement with the edges of the sole.

When adjusting the bracket 16 on the side bars 17, said brackets are first disengaged

or unlocked from said side bars by pressing upon the opposite sides of the lever 13 thereby moving the lower end portions of the loop arm 15 together and sliding the brackets 16 inwardly out of mesh with the inner serrated edges of the bars 17. The brackets are then placed in the desired position on the side bars 17 and by relaxing pressure on the opposite sides of the lever 13 the latter resumes its normal shape carrying the brackets back into mesh with the serrated inner edges of the side bars 17 thereby locking the brackets in adjusted positions.

The inturned flaps 2, 2 are punched to provide upstanding prongs 21 to engage with the tread side of the sole, thereby preventing slipping of the sole on the creeper.

The two end members 3 and 4 of the base of the creeper are adjustably connected with the body member 1 of said base as described so that the width of the creeper may be varied to fit soles of different widths, the three parts constituting the base being locked in their relatively adjusted positions by the engagement of the teeth or prongs 6 with the slots 7.

Secured in position upon the bottom side of the middle base member 1, and at opposite ends thereof, are two perpendicular walls 22 which are sinuous, or zig-zag, in shape. The lower edges of these walls 22 contact with the ground or supporting surface and, as will be clear, these walls 22 by engagement therewith and owing to their peculiar shape, will prevent slipping in any direction horizontally.

Between the side walls 22 there is provided a pad 23 which may conveniently be a molded piece of rubber having a roughened tread side. This pad 23 is held in position against the bottom side of the body or intermediate member 1 of the base by prongs 24 struck up from member 1 and turned over the opposite edges, front and rear, of the pad 23. Also, the end walls 22 assist in holding the pad 23 in position, said pad extending from one side wall 22 across to the opposite side wall.

As a matter of convenience in manipulating the hook 20 I may provide the same, as herein shown, with a pivoted wire ring or loop 25 adapted to serve as a handle.

The above described parts are organized and arranged so that when, in applying the creeper to a boot or shoe, the levers 13 are swung toward sole gripping position, they come into engagement with the sole before the spring bow arms 15 reach their final position so that continued inward pressure on said arms 15 flexes the latter more or less so that the lower portions of the levers 13 grip the sole with a pressure proportionate to the pull of stretched spring 19 and its effect upon the arms 15.

From the above description it will be clear that I have provided a simple and efficient creeper attachment for boots and shoes near-

ly all of whose parts are either bent wire or sheet metal stampings whereby the cost of production is reduced to the minimum.

What I claim is:

1. A creeper for boots and shoes comprising a base consisting of an intermediate body member and two oppositely disposed end members slidably and telescopically coupled to the body member to provide for adjustment thereof to accord with the width of the sole; means for locking said end members to said body member in their adjusted positions; upstanding abutments on said end members to engage the opposite edges of the sole, and sole clamping members pivotally connected with said abutments and engaging the top side of the sole.

2. A creeper for boots and shoes comprising a base consisting of an intermediate body member and two oppositely disposed end members slidably connected with the body member to provide for adjustment thereof to accord with the width of the sole; means for locking said end members to said body member in their adjusted positions; upstanding abutments on said end members to engage the opposite edges of the sole, sole clamping levers connected with said abutments and engaging the top side of the sole, and means connecting said levers and extending over the shoe for holding said levers in sole clamping positions.

3. A creeper for boots and shoes comprising a base consisting of an intermediate body member and two oppositely disposed end members slidably connected with the body member to provide for adjustment thereof to accord with the width of the sole, each of said end members being made at its outer end with an upstanding abutment ear to engage the edge of the sole; means for locking said end members to said body member in their adjusted positions; links pivotally connected with said abutment ears; sole engaging and clamping levers fulcrumed on said links, and means extending over the boot or shoe and connecting said levers for holding the latter in sole clamping positions.

4. A creeper for boots and shoes constructed in accordance with claim 3 and including also means to provide for adjustment of each lever on its link according to the thickness of the sole.

5. A creeper for boots and shoes constructed in accordance with claim 3 and including also a member mounted on each link providing the journal bearing for the lever of said link, said member being adjustable longitudinally of said link according to the thickness of the sole.

6. A creeper for boots and shoes constructed in accordance with claim 3 and wherein each link consists of a plate formed with a longitudinal slot bordered upon its opposite sides by toothed edges and including also

journal brackets slidably embracing the side bars of said links and adjustably interlocked with said toothed edges, said brackets supporting the fulcrums of said levers, each lever being made from wire and resiliently compressible laterally to disengage said brackets from the side bars of said link.

7. A creeper for boots and shoes comprising a sheet metal base member to fit against the tread side of the sole; means connected with the ends of said base member to extend

across the top of the shoe to hold the base member in position; zig-zag perpendicular walls upon the tread side of said base member, one near each end thereof, and a resilient pad occupying a position between and supported laterally by said walls. 15

Signed by me at Boston, county of Suffolk and State of Massachusetts, this 25th day of March, 1927.

HIRAM S. COBURN.
